DESIGN FOR A FOLDING COMBINATION BOTTLE AND CAN OPENER

Vernon C. Porter, New York, N. Y.

Application April 2, 1945, Serial No. 118,828

Term of patent 14 years

(Cl. D22—2)

To all whom it may concern:

Be it known that I, Vernon C. Porter, a citizen of the United States, residing at 310 Riverside Drive, New York 25, in the county of New York and State of New York, have invented a new, original, and ornamental Design for a Folding Combination Bottle and Can Opener, of which the following is a specification, reference being had to the accompanying drawing, forming a part thereof.

Fig. 1 is a top perspective view of a folding combination bottle and can opener showing my new design, and

Fig. 2 is a bottom perspective view drawn on a slightly reduced scale.

I claim:

The ornamental design for a folding combination bottle and can opener, as shown.

VERNON C. PORTER.
